UNITED STATES PATENT OFFICE.

LESTER L. JONES, OF ORADELL, NEW JERSEY.

ELECTRON-DISCHARGE-TUBE AMPLIFIER SYSTEM.

Application filed June 11, 1927. Serial No. 198,061.

This invention relates to an electron discharge tube amplifier system; and has special reference to the provision of a non-tunable amplifier system especially adapted for 5 use in the amplification of high radio frequencies and having a high amplification over a relatively wide wave length band.

The prime object of my present invention centers about the production of a system of 10 amplifying high, such as radio frequency vibrations, by means of electron tube or relay circuits having fixed or non-adjustable constants, which functions to produce high and efficient amplification over a considerable 15 or relatively wide wave length range or band.

Amplifier systems in which the circuit constants (capacity, inductance and resistance of the circuit) are fixed and non-adjustable 20 are known in the prior art as untuned amplifiers, and are characterized by the lack of uniformity in amplification, together with the great inefficiency of amplification in some 25 part of the frequency band. This objectionable characteristic is due to the fact that the amplification of such systems varies with the frequency impressed upon the system, the maximum amplification being produced at 30 the resonant frequency of the system. One of the important principles of my present invention resides in the production of electron discharge tube amplifier systems of this character, that is, embodying fixed or non-variable circuit constants, constructed and 35 designed however so that in lieu of producing an untuned system, there is produced a circuit arrangement or system which is self-tuning or is automatically tuned over a relatively wide wave length band resulting 40 in the obtaining of a uniformly high amplification over said wide wave length band.

The principal object of the invention may therefore be said to relate more specifically to the production of a high and reasonably 45 constant degree of amplification over a band such as, for example, a range of from 500 to 1500 kilocycles in circuits employing the electron discharge tube relay, which circuits have fixed constants or circuit adjustments 50 of inductance, capacity and resistance. From another aspect, the application of the principles of my present invention results in the transformation of a so-called untuned ampli-

fier into an automatically tunable amplifier, or an amplifier which is self-tunable over the 55 wave length band to produce uniformly high and efficient amplification over the band.

The principles of my present invention are applied in their preferred form to a triode or electron discharge device or tube having 60 grid, plate and filament electrodes, the said tube forming the coupling means between an input circuit having fixed circuit constants and an output circuit also having fixed constants. Broadly considered, I have discovered that the constants of both the input 65 and output circuits of said triode may be so predetermined and inter-related as to cause the input circuit to resonate or maintain its resonance at frequencies over the 70 wave length band or a considerable portion of the wave length band for which the system is designed, such band being, for example, the broadcast band of frequencies now in use.

Considered in its more specific aspects, I have discovered:

(1) That the constants, that is to say, the capacity, inductance and resistance, of the input circuit of the triode may be so fixed 80 that the production of a predetermined variation with frequency in the input capacity of the triode or tube over a given wave length band maintains the said input circuit resonant over said given wave length band, and 85

(2) That the constants of the output circuit may be so fixed or predetermined as to be effective with the change in frequency over said wave length band for producing that predetermined variation in the tube input capacity which results in the said maintaining of the input circuit resonant over 90 said wave length band.

By thus predetermining the constants of the input and output circuits and predetermining this relation therebetween, the circuit system, although devoid of variable or adjustable tuning elements such as are commonly employed in the prior art in tunable systems, is made to resonate for any 100 selected frequency over a wide frequency range.

To the accomplishment of the foregoing and such other objects as will hereinafter appear, my invention consists in the elements 105 and their relation one to the other, as here-

inafter more particularly described and sought to be defined in the claims; reference being had to the accompanying drawings which show the preferred embodiment of my invention, and in which:

Fig. 1 is a wiring diagrammatic view of an amplifier system embodying the principles of my present invention,

Fig. 2 is a graph showing the predetermined changes in the input capacity of the coupling tube or triode which causes the input circuit thereof to resonate at the frequencies over the band frequencies,

Fig. 3 is a graph showing the difference in amplification curves between an untuned system of the prior art and an automatically tuned system of my present invention,

Fig. 4 is a graph showing the effect produced on the input capacity of the tube or triode by the predetermined of the constants of the output circuit, and

Figs. 5^a and 5^b are graphs depicting the manner of inter-relating the characteristics or behaviours of the input and output circuits so as to produce the amplification efficiency desired over the wave length band.

Referring now more in detail to the drawings, and having reference first to Fig. 1 thereof, I show my invention applied to a cascaded electron discharge tube system having an electron discharge tube V1 forming the coupling means between an input network I and an output network O, the said input network embodying a transformer T1 which it is desired to keep in resonance with all the frequencies over a given wave length band, and the output circuit O including a transformer T2; the constants of said input and output circuits I and O respectively being fixed or made invariable. The input circuit I is shown as a radio frequency input coming from an electron discharge tube VO which may be another amplifier tube connected to any desired means for selecting a particular frequency over a given frequency range; and the output circuit O is shown connected to an output, as for example to an electron discharge tube V2 operating as a detector, which in turn has output terminals designated "output" which may be connected to the usual phones or to an audio amplifier network. Each of the electron discharge devices comprises a three-electrode tube having a grid g, plate p and filament f.

The detector tube V2 may be provided with the grid leak or integrating device g1; and the various input and output terminals are connected in a manner well known to the art to the A and B batteries or equivalent sources of energy designated as A-, A+ and B+.

In this circuit system of Fig. 1, the input circuit I, and more specifically the transformer T1, is desired to be kept in resonance with all of the frequencies selected by the

circuit network preceding the input I over the desired wave length range. In accordance with my invention, to hold this resonant condition the total capacity across the transformer T1 must be varied proportionately to the square of the wave length. This total capacity I show in phantom or dotted line in Fig. 1 of the drawings as C, the same being shown as variable since this capacity C must be varied to maintain the resonant condition. This total capacity is made up of a fixed amount corresponding to the distributed capacity of the primary and secondary coils p' and s' of the transformer T1, the plate to grid and filament capacity of the preceding tube VO, the connections from the transformer T1 to the grid and plate of both tubes VO and V1, and the grid filament capacity of the tube V1 (this is all fixed) and a variable amount which is the grid-plate capacity of the tube V1. This total capacity is denoted and will be referred to herein as the tube input capacity. This variable grid-plate capacity is a function of the frequency and of the output load (the transformer T2 and the following circuits connected thereto). In order to maintain the resonance of the input circuit I or the transformer T1, the tube input capacity C must increase with decreasing frequency.

This requirement of the characteristics of the input circuit to maintain resonance is shown by the graph in Fig. 2 of the drawings, in which the ordinates represent the resonant wave lengths of the transformer T1 and the abscissae represent the capacities which will keep this transformer resonant at the various frequencies. In this graph the curve abc represents the performance of the transformer T1, which transformer is designed to have a natural wave length at about 205 meters. The full line portion bc of the curve shows the performance of the transformer beginning with the wave length at which the transformer oscillates when shunted with a total capacity of approximately 30 mmfds.; and the dotted part ab of the curve is an extrapolation for determining the minimum capacity of the input circuit. This value of minimum capacity corresponds to the lowest values of the tube and transformer coil capacities that can be secured with good engineering design and present-day reliable commercial amplifier tubes. The curve shows how much additional capacity (C) must be added across the transformer T1 in order to secure wave lengths greater than 205 meters. For example, in order to secure 400 meters it would be necessary to add about 88 mmfds. to the minimum capacity.

As aforesaid, I have discovered that this variation in the tube input capacity may be obtained by selecting the characteristics

of the output circuit constants. The desired increase or variation of the tube input capacity C is supplied by an increase of the grid-plate capacity of the tube V1, which 5 increase is secured by selecting a transformer T2 having constants which are effective with the change in frequency over the wave length band for producing the desired variation of the tube input capacity over the said wave 10 length band.

The factors which govern the selection of the characteristics of the transformer T2 are determined from the behaviour of the transformer as to its effect on producing the 15 variation in the input capacity C. In Fig. 4 of the drawings I show curves which depict the behaviour of transformers having suitable physical characteristics. I have found that every transformer produces a 20 certain change of tube input capacity with frequency. The simplest case is where the transformer has no leakage inductance and is therefore in the nature of a simple inductance. The form of the tube input ca- 25 pacity curve is similar to the resonance curve of the transformer as shown in Fig. 4 of the drawings wherein is depicted curves of transformers, the ordinates of the graph of Fig. 4 representing the added input ca- 30 pacities (C) and the abscissæ representing the impressed wave length.

The curve B—B of the graph of Fig. 4 shows the variation in the input capacity produced in the tube V1 when the same is 35 followed by a transformer which I designate as a bifilar transformer, to be described hereinafter, having a resonant wave length of approximately 400 meters (with a total capacity across it of 30 mmfds.). Curve 40 A—A on the graph of Fig. 4 shows the variation in tube capacity of the tube V1 produced by a transformer T2 in which the coils are placed exceedingly close together, separated only by thin mica sheets. This 45 transformer has a slightly higher natural wave length, but the form of the curves A—A and B—B is the same. It will be noted that there is an increase of tube input capacity from 10 mmfds. at 100 meters to 50 approximately 70 mmfds. at 400 meters. As will be shown hereinafter, the self or automatic tuning of the transformer T1 is accomplished by the rising tube input capacity corresponding to that section of the curves 55 at the left of the peak thereof.

It will now be apparent from a comparison of Figs. 4 and 2 that the characteristics of the transformer T2 for producing the input capacity change with frequency may be 60 so selected as to coincide with the characteristics of the input circuit or transformer T1 of producing the resonance over the wave length range by the variation of the input capacity C. This is shown in Figs. 5^a and 45 5^b, Fig. 5^a showing the curve of Fig. 2 with

the wave lengths as the abscissæ and the change in capacity across the transformer T1 as the ordinates, and Fig. 5^b showing the curve of Fig. 4 designed so as to have a component or section at the left of the peak 70 thereof which may be made to coincide with the curve of Fig. 5^a.

I have found by empirical determination that these curves may be made to coincide by suitably selecting the characteristics of the 75 fixed constants of the transformers T1 and T2. To accomplish the desired end, with given selective characteristics of the transformer T1, I select the characteristics of the transformer T2 firstly with respect to the 80 rate change of tube input capacity, and secondly with respect to the frequency corresponding to the minimum and maximum of the tube input capacity. The desirable rate change of tube input capacity is basically determined by a curve such as that shown in Fig. 5^a; and this is determined mainly by the physical form of the transformer T2, and more specifically by the distributed capacity of the coils thereof and 85 more especially by the magnetic leakage between the primary and secondary coils p^2 and s^2 thereof. As a general principle it may be stated that the less the magnetic leakage, the slower the variation of tube input capacity with frequency, and the lower the distributed capacity of the transformer, the greater the relative magnitude of the tube input capacity change. The minimum and maximum points of the curve of Fig. 90 5^b, that is, the second characteristic of the transformer T2, is determined for any one physical form of transformer by suitably selecting the inductance of the windings so that the said transformer T2 has a natural 95 frequency corresponding to the lowest frequency of the wave length band. Thus, if the wave length band is 1500 to 500 kilocycles, the natural frequency of the transformer T2 would be selected to be slightly 100 lower than 500 kilocycles, as for example, 470 kilocycles. This natural frequency of the transformer T2 is selected in this wise because at this natural frequency of the transformer T2, the tube input capacity of 105 the tube V1 is a maximum, as shown by the curve of Fig. 5^b, and the maximum tube input capacity is necessary in order to maintain the preceding transformer T1 resonant to 110 this lower frequency, as shown by the curve 115 of Fig. 5^a of the drawings.

Decrease in capacity of the required form is secured by arranging the transformer structure to create a similar form of equivalent resistance. This problem may also be attacked by arbitrarily changing the fixed 120 value of capacity across the transformer T1 at the higher end of the frequency band. If, for example, additional capacity is added to T1, then a larger variation of the tube in- 125 130

put capacity will tune over a narrower frequency band. The straight characteristic of the curve of Fig. 5^b between the beginning and peak points thereof is determined, as aforesaid, by the physical characteristics of the transformer, determining a form of curve generally similar to the tuning requirements of Fig. 5^a with first, freedom from leakage inductance to avoid points of inflection in the tube input capacity curve, and second, relatively low distributed capacity to insure a relatively slow rate of change of tube input capacity with frequency.

Since the transformer structures are broadly tuned by this, that is, the change in response with frequency change is small, it is not necessary to have the terminal capacity exactly correct. A deviation of 16% or 20% in the actual capacity from that which is theoretically required would produce only 5% deviation in the resonant frequency from the impressed frequency. This change in response due to a 5% frequency change would be relatively small so that the sacrifice in efficiency due to lack of coincidence of these curves is very small. It is only necessary that the curves of Figs. 5^a and 5^b have approximately the same starting and ending points and that their form in between these points be generally similar.

The preferred method of obtaining the minimum distributed capacity and minimum leakage inductance of the transformers T1 and T2 will now be described. Minimum distributed capacity is generally desirable for two reasons, first, because a small capacity across a transformer at radio frequencies tends to increase the voltage obtainable, and second, because the minimum capacity extends the frequency band over which automatic tuning may be secured, since this band is dependent upon the initial capacity. The minimum leakage inductance is desirable firstly, to secure the maximum induced voltage in the secondary of the transformer, and secondly, to eliminate the second or short wave mode of oscillation of the transformer. I have found that to produce this minimum distributed capacity and minimum leakage inductance the transformer should be wound bifilarly as disclosed in my copending application to a transformer and coil system, Serial No. 195,631, filed June 1, 1927.

This bifilar transformer comprises briefly a transformer having primary and secondary windings wound by taking two filaments, arranging the same in close juxtaposition throughout their entire lengths, this being preferably accomplished by winding the transformer with a pair of wires twisted together with a pitch relatively large compared to the wire diameter. One of these wires forms the primary winding and the other the secondary winding, similar ends of the two windings being connected to the

plate voltage supply and the filament connection of the tube. The bifilar winding is preferably random wound in a relatively narrow slot so as to yield a coil of relatively small distributed capacity and of relatively high inductance, the inductance being made sufficiently great to give a natural frequency to the transformer in connected circuit corresponding to the lowest frequency of the wave length band for which the system is designed.

Preferably both of the transformers T1 and T2 are bifilar transformers having similar characteristics, the inductance of the transformer T2 being however higher than T1 so that the natural frequency of the transformer T2 is generally lower than the natural frequency of the transformer T1. This produces an increase of tube input capacity from the higher frequencies to the lower frequencies corresponding to the natural frequency of the transformer T2. As an example of the application of my invention I shall assume that the relay tubes have amplification constants of 8, grid plate capacities of 10 mmfds. and grid filament and plate filament capacities of approximately 10 mmfds. The total capacity hanging into a transformer such as T1 would therefore be of the order of 30 mmfds. To resonate at about 200 meters this transformer T1 should have an inductance of about 360 microhenrys. This is where the transformer has substantially zero leakage, as in the case of the bifilar type. Where the transformer has substantial leakage the computation of its long wave natural frequency is more difficult, and it is best to adjust the transformer experimentally to the desired natural frequency. In such a system the transformer T2 should have an inductance of approximately 2-3 millihenrys so as to resonate at about 600 kilocycles. The tube input capacity of the vacuum tube V1 would then increase by approximately 70 mmfds. at this low frequency so that the preceding transformer would be resonant to about 800 kilocycles when the impressed frequency is 600 kilocycles, producing a substantial coinciding of resonance. More exact matching of the transformer resonance with the frequency may be secured by the use of either tubes having lower grid filament and plate filament capacities or by the use of tubes having a higher amplification constant.

It is seen therefore that the first transformer T1 is preferably arranged to have a natural of 1500 kilocycles so that it is resonant at 200 meters when the tube input capacity is a minimum. The tube input capacity is a minimum at 200 meters because this frequency is so far removed from the frequency of the transformer T2 that transformer T2 causes a very slight change of the tube input capacity from the normal mini-

imum value. Transformer T₂ is given the natural frequency near the lower limit of the frequency band (550 to 600 kilocycles) so as to both tune the first transformer T₁ up to 5 or near this wave length and to provide the highest amplification by means of the relay tube. The lower the frequency to which T₂ is tuned, the higher its impedance may be made, and therefore the higher the amplification 10 to be secured from it. In speaking of the natural frequency of the transformer I mean a frequency which is determined by the inductance of the transformer and the capacities attached to it. The simplest case 15 is where the capacities attached to the transformer are constant. This is the case where the transformer works into a detector tube as shown in Fig. 1 of the drawings. These capacities may be measured at any 20 frequency and the natural of the transformer may be computed and so predetermined from the coil inductances and the measured capacities.

The results accomplished by constructing 25 a cascade amplifier system such as hereinbefore described is shown in Fig. 3 of the drawings wherein is depicted the difference between an untuned stage constructed in accordance with the prior art and an automatically tuned stage constructed in accordance 30 with the principles of the present invention. The dotted line curve in Fig. 3 shows the amplification obtained with an untuned stage of the prior art and the full 35 line curve shows how the amplification of a system of my present invention instead of decreasing from a peak or maximum is maintained substantially constant over the wave length range. In producing the desired 40 resulting amplification curve the precaution should be observed of building the transformer T₂ with a natural wave length within a given range. It is found that when this transformer is constructed to have the 45 shorter natural wave lengths, the resulting amplification becomes peaky. For example, a wave length shorter than 450 meters for the transformer T₂ creates a peaky condition which soon runs into an unstable or oscillatory 50 condition. This phenomena I designate as overtuning and should be avoided in the design of the transformer. When the transformer T₂ has too short a natural wave length, the tube input capacity of the 55 tube V₁ rises so fast with frequency as to cause transformer T₁ to have a natural frequency of oscillation lower than the natural frequency of T₂. In this condition the tube T₂ exerts a very strong regenerative feed- 60 back effect on the tube T₁ and creates a sharply peaked regenerative gain in amplification with its undesirable instability in the amplifier and the production of currents of local oscillations.

65 The use and operation of the amplifier

system embodying the principles of my present invention and the numerous advantages thereof will in the main be fully apparent from the above detailed description thereof. It will be further apparent that 70 while I have shown and described my invention in the preferred form, many changes and modifications may be made in the structure disclosed without departing from the spirit of the invention, defined in the following 75 claims.

I claim:

1. An electron discharge tube amplifier system comprising an electron discharge tube having input and output electrodes, an inductive input circuit connected to the input electrodes, the said input circuit having fixed constants including a given tube input capacity, and an impedance output circuit network connected to the output electrodes, 80 the said impedance output circuit network having constants effective with the change in frequency over a given wave length band for varying the said tube input capacity over said wave length band so as to maintain the 85 inductive input circuit resonant over said given wave length band.

2. An electron discharge tube amplifier system comprising an electron discharge tube having input and output electrodes, an input circuit connected to the input electrodes and including a transformer, the said input circuit having fixed constants including a given tube input capacity, and an output circuit network connected to the output electrodes, 90 the said output circuit network including a second transformer, the said second transformer in connected circuit having constants effective with the change in frequency over a given wave length band for varying the said tube input capacity over said wave length band so as to maintain the 95 said input circuit resonant over said given wave length band.

3. An electron discharge tube amplifier system comprising an electron discharge tube having input and output electrodes, an input circuit connected to the input electrodes and including a bifilarly wound transformer, the said input circuit having fixed constants including a given tube input capacity, and an output circuit network connected to the output electrodes including a second bifilarly wound transformer, the said second transformer having constants effective with the change in frequency over a given 110 wave length band for varying the said tube input capacity over said wave length band so as to maintain the inductive input circuit resonant over said given wave length band.

4. An electron discharge tube amplifier system comprising an electron discharge tube having input and output electrodes, an input circuit connected to the input electrodes and including a bifilarly wound transformer, the said input circuit having fixed constants in- 120

cluding a given tube input capacity, and an output circuit network connected to the output electrodes including a second bifilarly wound transformer, the said second transformer having constants effective with the change in frequency over a given wave length band for varying the said tube input capacity over said wave length band so as to maintain the inductive input circuit resonant over said given wave length band, the filaments of each of said transformers being wound in close juxtaposition to produce a minimum distributed capacity in and a minimum magnetic leakage between the coils of the transformer.

5. An electron discharge tube amplifier system comprising an electron discharge tube having grid, plate and filament electrodes, an inductive input circuit connected to the grid and filament electrodes, the said input circuit having fixed constants and the said tube having capacity between the grid and plate electrodes, and an impedance output circuit network connected to the plate and filament electrodes, the said impedance output circuit having constants effective with the change in frequency over a given wave length band for varying the said grid-plate capacity over said wave length band so as to maintain the inductive input circuit resonant over said given wave length band.

6. An electron discharge tube amplifier system comprising an electron discharge tube having grid, plate and filament electrodes, an input circuit connected to the grid and filament electrodes including a transformer, the said input circuit having fixed constants and the said tube having capacity between the grid and plate electrodes, and an output circuit network connected to the plate and filament electrodes and including a second transformer, the said second transformer having constants effective with the change in frequency over a given wave length band for varying the said grid-plate capacity over said wave length band so as to maintain the inductive input circuit resonant over said given wave length band.

7. An electron discharge tube amplifier system comprising an electron discharge tube having grid, plate and filament electrodes, an inductive input circuit connected to the grid and filament electrodes, the said input circuit having fixed constants and the said tube having capacity between the grid and plate electrodes, and an impedance output circuit network connected to the plate and filament electrodes, the said impedance output circuit network including a bifilarly wound transformer having constants effective with the change in frequency over a given wave length band for varying the said grid-plate capacity over said wave length band so as to maintain the inductive input

circuit resonant over said given wave length band.

8. An electron discharge tube amplifier system having a high amplification over a relatively wide wave length band comprising an electron discharge tube having input and output electrodes, an inductive input circuit connected to the input electrodes, the said input circuit having fixed constants including a given tube input capacity, and an impedance output circuit network connected to the output electrodes, the said impedance output circuit network having a natural frequency corresponding to the lowest frequency of said wave length band so as to be effective with the change in frequency over said wave length band for varying the said tube input capacity to maintain the inductive input circuit resonant over said given wave length band.

9. An electron discharge tube amplifier system having a high amplification over a relatively wide wave length band comprising an electron discharge tube having input and output electrodes, an inductive input circuit connected to the input electrodes, the said input circuit having fixed constants including a natural frequency corresponding to the highest frequency of said wave length band and also including a given tube input capacity, and an impedance output circuit network connected to the output electrodes, the said impedance output circuit network having a natural frequency corresponding to the lowest frequency of said wave length band so as to be effective with the change in frequency over said wave length band for varying the said tube input capacity to maintain the inductive input circuit resonant over said given wave length band.

10. An electron discharge tube amplifier system having a high amplification over a relatively wide wave length band comprising an electron discharge tube having input and output electrodes, an input circuit connected to the input electrodes and including a transformer, the said input circuit having fixed constants including a given tube input capacity, and an output circuit network connected to the output electrodes and including a second transformer, the said second transformer having a natural frequency corresponding to the lowest frequency of said wave length band and having low distributed capacity in and low magnetic leakage between the coils thereof so as to be effective with the change in frequency over said wave length band for varying the said tube input capacity to maintain the inductive input circuit resonant over said given wave length band.

11. An electron discharge tube amplifier system comprising an electron discharge tube having input and output electrodes, an in-

ductive input circuit connected to the input electrodes, the said input circuit having fixed constants including a given tube input capacity, the said constants being such that a predetermined variation in said tube input capacity over a given wave length band maintains the said input circuit resonant over said given wave length band, and an impedance output circuit network connected 5 to the output electrodes, the said impedance output circuit network having constants effective with the change in frequency over said wave length band for producing the said predetermined variation in said tube input capacity.

12. An electron discharge tube amplifier system comprising an electron discharge tube having grid, plate and filament electrodes, an input circuit connected to the grid 20 and filament electrodes and including a transformer, the said input circuit having fixed constants and the said tube having capacity between the grid and plate electrodes, the said constants being such that a predetermined variation in said grid-plate capacity over a given wave length band maintains the said input circuit resonant over said given wave length band, and an impedance output circuit network connected to the plate 25 and filament electrodes and including a second transformer, the said impedance output circuit network having constants effective with the change in frequency over said wave length band for producing the said predetermined variation in said grid-plate capacity.

13. An electron discharge tube amplifier system comprising an electron discharge tube having input and output electrodes, an input circuit connected to the input electrodes 40 and including a transformer, the said input circuit having fixed constants including a

given tube input capacity, the said constants being such that a predetermined variation in said tube input capacity over a given 45 wave length band maintains the said transformer input circuit resonant over said given wave length band, and an output circuit network connected to the output electrodes including a second transformer, the said second transformer having constants effective with the change in frequency over said wave length band for producing the said predetermined variation in said tube input capacity.

14. An electron discharge tube amplifier system having a high amplification over a relatively wide wave length band comprising an electron discharge tube having input and output electrodes, an input circuit connected to the input electrodes and including a transformer having a natural frequency corresponding to the highest frequency of said band, the said input circuit having fixed constants including a given tube input capacity, the said constants being such that a predetermined variation in said tube input capacity over a given wave length band maintains the said input circuit resonant over said given wave length band, and an impedance output circuit network connected to the output electrodes and including a second transformer, the said second transformer having a natural frequency corresponding to the lowest frequency of said wave length 65 band so as to be effective with the change in frequency over said wave length band for producing the said predetermined variation in said tube input capacity.

Signed at New York, in the county of 80 New York and State of New York, this 8th day of June A. D., 1927.

LESTER L. JONES.
